PUTTING GAME TARGET

Hyman B. Lasting, Portsmouth, Va., assignor to Putt-Well Golf Corporation, Virginia Beach, Va., a corporation of Virginia

Filed Oct. 13, 1965, Ser. No. 87,457

Term of patent 14 years

(Cl. D34—5)

FIG. 2 is a side view looking in from the right-hand side of FIG. 1, the opposite or left-hand side having substantially the same appearance;

FIG. 3 is a sectional view taken on line 3—3 of FIG. 1 looking in the direction of the arrows;

FIG. 4 is a perspective view thereof.

I claim:

The ornamental design for a putting game target, as shown and described.
